UNITED STATES PATENT OFFICE

MORRIS W. BECKER, OF NEW YORK, N. Y.

THREAD COATING, WAXING, AND IMPREGNATING ATTACHMENT FOR WINDING MACHINES

Application filed November 22, 1928. Serial No. 321,175.

This invention relates to a new device to be attached to thread winding machines, for coating, waxing or for impregnating threads, on both sides, with such substances as wax, resinous or other impregnating or coating compositions and materials, in which contrivance, before the thread is wound on spools or paper cones by the winding machine, the thread is permitted to pass through this invention which is attached to the winding machine so as to be in the thread's running path, and thereby the thread becomes coated or impregnated on both its sides with any material desired.

Threads used in sewing machines must be so treated by being coated with various materials so that in passing through needles and other places of tension, the thread runs smoothly and does not break; the coating thus serves as a lubricant. It is important however that the thread be fully coated, or as expressed herein, to be coated on both sides. Also, various trades require threads or twines to be coated or impregnated with various compositions and substances, and this invention affords a suitable, convenient and inexpensive means to affect such purposes by having the thread while in motion on the winding machine, to pass through this invention before actually wound on spools or paper cones by said winding machines upon which this contrivance will be an attachment, one for each winding spindle.

The elements of this invention are set forth in the following description and the purposes of this invention are attained by the mechanism or contrivance illustrated in the accompanying drawings, which are hereby made a part of this specification.

Fig. 1 is a front elevation of the attachment.

Fig. 2 is a fragmentary view showing a portion of the angle frame.

Fig. 3 shows the reversing guide.

Fig. 4 shows a spindle plate upon which a waxing cylinder is placed.

Fig. 5 shows a pin upon which a spindle plate revolves.

Fig. 6 is a side elevation of the attachment.

Fig. 1 shows this invention and its relative position on a thread winding machine. This

invention consists of an angle frame A which is attached to the winding machine by a bar or bracket W. Into each of the arms of said frame A fastened by nuts H is set pin C, upon each of which two pins C freely revolves the spindle-plate contrivance shown in Fig. 4. On each spindle E, there being two to this invention, is set on a moulded cylinder of wax or other substance D₁ and D₂ with which it is desired to coat the thread. These cylinders D₁ and D₂ fit very loose and are free to turn on spindles E and they rest on plates F which are turned down a little on their ends as is shown in Fig. 4. The frame A has in it a slot K as shown in Fig. 2 permitting guide shown in Fig. 3 to be set on bracket A by clamp-fit slot L. P₂ commonly called a pigtail is a turn of wire and the thread is set into it to be guided before it reaches R which is a part of the thread winding machine whose function it is to guide the thread on the cone S which is the form in which the thread is sold in commercial use.

The thread T being wound off from spool Y passes through X a mechanism which gives the thread tension then the thread passes through the invention herein by passing on guide pin P₁ and then the thread passes between plate F and cylinder D₁ the weight of D₁, pressing on thread which is in motion by virtue of the mechanism of the winding machine proper causes that side of the thread uppermost against D₁ to be coated with the material, the thread in its motion wears off from cylinder D₁, and plate F is turned down around its end as shown in Fig. 4 in order to provide a smooth path for the thread T which now passes through slot K against guide M at point M₁, which point is just in line of motion of the thread and the thread follows around guide M to point M₂, which is just in line of the running thread T to enter between plate F and cylinder D₂. When the thread passes under the cylinder D₂, the side which was waxed or coated by passing under cylinder D₁ is now against plate F and the side which was not coated is now uppermost against cylinder D₂ so that the thread in its motion and by virtue of having cylinder D₂ press upon it due to its own weight causes

the uncoated side of the thread to become coated and thus the thread has become fully coated on both its sides with the material composing cylinders D_1 and D_2 ; guide M serving as a means to reverse the waxed side of the thread and to guide the unwaxed side of the thread to engage with the second waxing cylinder D_2 , and such office of M being its main function. The thread now passes 10 through guide P_2 and then is engaged by guide R a part of the winding machine which directs the thread T onto cone S .

This invention, therefore, provides, a suitable means to fully coat threads on both of 15 its sides while they are being wound, with any substance the thread may be required to be coated with. The guide M also provides a smooth path for the running thread T , and the thread is likewise aided by having the 20 plates F turned down a little on their ends.

Fig. 4 shows the spindle-plate upon which the cylinders D_1 and D_2 are placed. Two such cylinder plates are necessary for this 25 invention and are set on pins C and are free to turn on same through hole G in cap Z fitted on to tube E which has a little cap similar to cap Z with a hole size E set in at the bottom of tube E in the plane of plate F .

Fig. 5 shows the pins C thread a little up 30 their length to point J and such pins are set into frames A in their relative positions as shown in Fig. 1 by having two nuts H hold each pin in place through holes in angles frame A .

35 I claim as my invention:

1. A thread waxing device comprising an angle frame, two pins set one into each arm of said angle frame, which pins are each adapted to receive a wax cylinder moving 40 axially and circularly thereon, and interposed between said pins at the bend in the frame, a means to reverse the side of the thread first exposed for waxing, and means to guide the unwaxed side of the thread to engage with the second of said wax cylinders.

45 2. A thread waxing device comprising an angle frame, two pins set one into each arm of said angle frame, which pins are each adapted to receive rotatable mounted spindle plates, and each of which spindle plates are adapted to receive a cylinder of wax moving axially and circularly thereon, and interposed between said pins at the bend in the frame, a means to reverse the side of the 50 thread waxed by the first of said cylinders of wax and means to guide the unwaxed side of the thread to engage with the second of said cylinders of wax.

55 In testimony whereof, I affix my signature.
60 MORRIS W. BECKER.
